UNITED STATES PATENT OFFICE.

CHARLES A. SORIANO, OF BROOKLYN, NEW YORK, ASSIGNOR OF ONE-HALF TO
MARCO SCISCIO, OF BROOKLYN, NEW YORK.

TRUSS.

Application filed July 21, 1927. Serial No. 207,472.

This invention relates to trusses and comprehends an improved supporting element for the truss pad.

One of the principal objects of the invention is to provide in a truss, an improved pad-supporting element which equalizes the pressure while exerting a sufficient pressure to hold the pad in proper relation to the rupture, and this without marking the body or causing undue discomfort to the wearer.

More specifically the invention comprehends a truss pad-supporting element constructed of a yieldable or elastic tubing which prevents marking of the body and is therefore particularly adapted for use upon infants.

Other objects reside in the simplicity of construction, the economy with which the same may be produced, and the general efficiency derived therefrom.

With the above recited and other objects in view, reference is had to the following description and accompanying drawings in which there is exhibited one example or embodiment of the invention, while the appended claims define the actual scope of the invention.

In the drawings—

Figure 1 is a perspective view of a truss equipped with a pad-supporting element constructed in accordance with the invention;

Fig. 2 is a sectional view on an enlarged scale illustrating the manner in which the supporting element is associated with the pad;

Fig. 3 is a sectional view on an enlarged scale of the means for detachably anchoring the free end of the pad-supporting element;

Fig. 4 is a perspective view of the double truss employing a pad-supporting means constructed in accordance with the invention;

Fig. 5 is a sectional view on an enlarged scale of the pad element used in connection with a double truss;

Fig. 6 is a sectional view similar to Fig. 5 showing the use of the pad element shown in Fig. 5 as a single truss.

Referring to the drawings by characters of reference, 10 designates a truss pad, which is of any desired configuration and which is

preferably recessed or rabbeted at 11 and further provided with a passage or bore 12. In a single truss, the supporting element 55 which is preferably of elastic or yieldable tubing 13, has one terminal 14 thereof arranged within the recess or rabbeted portion 11 and anchored in place by suitable fastening means, such as a screw 15. The free end 60 of the tubing or supporting element 13 is trained through the passage or bore 12 to define an abdominal encircling loop 16, the remaining portion of which is adapted to be trained under the crotch with the terminal 65 or extremity 17 detachably associated with the looped portion 16. In order to detachably hold the terminal 17 in associated relation with the looped portion 16, a bendable ductile or malleable length of material 70 18 is arranged within the terminal 17, the same being of lead or any other suitable soft metal which is bendable and retains its bent position until bent to another form.

If a double truss is to be used for a double 75 rupture, the looped portion 16 is trained through a passage or bore 19 of a second pad 20, before training the same through the bore or passage 12 of the first-mentioned pad, and the second pad is provided with a sec- 80 ond bore or passage 21 in which a support- 85 ing element 22 also composed of tubing, is anchored at one extremity, the remainder of said element 22 being trained through the crotch and detachably fastened at its termi- 90 nal 23 in a similar manner.

In employing the pad element 20 in the capacity of a single truss, the supporting ele- 95 ment 22 which is provided with a plug 24 in its terminal having a stop element, such as 90 a pin 25 projecting therefrom, is initially trained through the bore 19 with the pin or stud 25 engaging the wall notch 26. The remainder of the supporting element 25 is formed into a loop form and is then passed 95 through the bore 21 with the remaining por- 100 tion trained through the crotch and the terminal engaged with the loop portion. It will thus be seen that the pad element 20 may be employed in the capacity of a single 100 or double truss.

From the foregoing it will thus be seen that an improvement in truss pad-supporting elements has been devised which effectu-

ally accomplishes the purpose with practically no discomfort to the user.

What is claimed is:

1. A truss including a pad-supporting element composed of a yieldable tubular material.
2. A truss including a pad-supporting element composed of elastic tubing.
3. A truss including a pad having a passage therethrough, and supporting means therefor consisting of a yieldable tubing attached at one end to the pad and having the opposite end extending through the passage to form an abdominal encircling loop.
4. A truss including a pad having a passage therethrough, and supporting means therefor consisting of a yieldable tubing attached at one end to the pad and having the opposite end extending through the passage to form an abdominal encircling loop, the

said free end of the tubing having means for detachably anchoring the same to the looped portion.

5. A truss including a pad having a passage therethrough, and supporting means therefor consisting of a yieldable tubing attached at one end to the pad and having the opposite end extending through the passage to form an abdominal encircling loop, the said free end of the tubing having means for detachably anchoring the same to the looped portion, said means consisting of ductile material within the free extremity of the tubing adapted to be bent around the looped portion thereof.

Signed at New York city in the county of New York and State of New York this 19th day of July, 1927.

CHARLES A. SORIANO.
